(57) **CLAIM**

The ornamental design for a handheld laparoscopic surgical instrument, as shown and described.

DESCRIPTION

FIG. 1 is a rear, right side perspective view of the handheld laparoscopic surgical instrument;

FIG. 2 is a rear, left side perspective view thereof;

FIG. 3 is a front, left side perspective view thereof;

FIG. 4 is a front, right side perspective view thereof;

FIG. 5 is a rear view thereof;

FIG. 6 is a front view thereof;

FIG. 7 is a right side view thereof;

FIG. 8 is a left side view thereof;

FIG. 9 is a top view thereof; and,

FIG. 10 is a bottom view thereof.

In FIGS. 1-10, a handle, an end effector, and pulley covers of the handheld laparoscopic surgical instrument are presented in broken lines.

The broken lines in the drawings illustrate portions of the handheld laparoscopic surgical instrument that form no part of the claimed design.
